Arthur L. Breitenstein
Hull, Smith, Brock & West Attn:

UNITED STATES PATENT OFFICE.

ARTHUR L. BREITENSTEIN, OF AKRON, OHIO, ASSIGNOR TO THE ASHLAND TIRE & RUBBER COMPANY, OF CLEVELAND, OHIO, A CORPORATION OF OHIO.

DESIGN FOR A VEHICLE-TIRE.

55,240.

Specification for Design.

Patented May 25, 1920.

Application filed December 4, 1919. Serial No. 342,559. Term of patent 7 years.

To all whom it may concern:

Be it known that I, ARTHUR L. BREITENSTEIN, a citizen of the United States, residing at Akron, county of Summit, and State of Ohio, have invented a new, original, and ornamental Design for Vehicle-Tires, of which the following is a specification, reference being had to the accompanying drawing, forming part hereof.

Figure 1 is a plan view of a portion of a vehicle tire, and Fig. 2 a section through the same showing my new design.

I claim:

The ornamental design for a vehicle tire as shown.

ARTHUR L. BREITENSTEIN.
